UNITED STATES PATENT OFFICE.

PAUL PETRES, OF LONG ISLAND CITY, NEW YORK.

TWIN AEROPLANE-PROPELLER.

1,364,580.

Specification of Letters Patent. Patented Jan. 4, 1921.

Application filed June 10, 1920. Serial No. 387,816.

To all whom it may concern:

Be it known that I, PAUL PETRES, citizen of Hungary, residing at Long Island City, in the county of Queens and State of New York, have invented certain new and useful Improvements in Twin Aeroplane-Propellers, of which the following is a specification.

This invention relates to aeroplanes and especially to the propelling mechanism thereof.

In the operation of an aeroplane propeller, which is usually placed at the front part of the machine, there is a certain amount of "slippage" whereby the linear distance traveled by the propeller in one revolution thereof is not equal to the lead or pitch of the propeller blades. Due to this slippage, a strong current of air is set up behind the propeller, the power necessary to produce said current having heretofore been wasted.

As one of the objects of this invention, I provide an auxiliary propeller behind the driving propeller for the purpose of obtaining power from the air current mentioned.

A further object of this invention is to provide a power plant capable of rotation with said auxiliary propeller in a direction opposite to that of the main driving propeller.

Other objects of the invention will appear from the description which follows, reference being had to the accompanying drawings, in which,

Figure 1 is a front view of my invention wherein a three cylinder gasoline engine is shown as the power generator.

Fig. 2 is a bottom view and partial section of the same.

Fig. 3 is an enlarged horizontal section on line 3-3 of Fig. 2.

Fig. 4 is a vertical section on line 4-4 of Fig. 3, and

Fig. 5 is a perspective view of an aeroplane to which my invention has been applied for driving and for vertically lifting said aeroplane.

In the practical embodiment of my invention, a motor 10 of any suitable type is suitably secured to an auxiliary propeller 11, as by braces 12 secured to the hub 13 of propeller 11 and to crank case 14 of motor 10, so that rotation of propeller 11 carries the entire motor 10 around with it.

The size of said propeller is such that it produces an appreciable amount of power with a comparatively small unit pressure

on the blades thereof, the pitch of said blades and the direction of the rotation thereof being opposite to that of the main driving propeller 15, which is suitably mounted for rotation by motor 10. The support for auxiliary propeller 11 comprises the hollow shaft 16 mounted for rotation on the stationary inner hollow shaft 17, suitable ball bearings 18 being provided between the rotatable shaft 16 and the frame 19, in which said shafts are mounted, said propellers 11 and 15 and shafts 16 and 17 being coaxially arranged. Shaft 17 is connected to a source of fuel supply, a suitable packing 20 serving to prevent the fuel from leaking at the joint between the movable and stationary shafts. At the end of shaft 17 is the hollow cap 21 from which the fuel supply pipes 23 are connected to the various cylinders of the motor 10.

While I illustrate a three cylinder gasoline driven motor, I do not wish to limit myself to this type of engine, since the broad principle here involved can be utilized for power economy even when other types of engines, such as gasoline or oil driven engines having any number of cylinders or other types of engines adapted for driving aeroplanes, are used, by being rotated together with an auxiliary propeller.

The frame 19 may be part of the aeroplane framing or it may be the front part of the fuel tank, the only requirement therefor being that it be made of sufficient strength to support the motor 10, the propeller 11 and the parts carried thereby.

It will be seen that, since the motor 10 is rotatable with respect to frame 19, a rotary arrangement for distributing the current to the various cylinder spark plugs is desirable, when an internal combustion motor is used. To the accomplishment of this end, I attach the ring disk 24 to frame 19 by bolt 25 and a nut 26 on the end of said pin, a second nut 27 serving to hold one wire 28 carrying electrical current from a source not shown.

Suitable insulation 29 prevents the current from passing through frame 19. For conducting the current from disk 24 to the distributor, a metallic spring 30 is pressed in contact with disk 24 by hub 13 of propeller 11, a wire as 31 leading from a terminal on said spring 30 to binding post end 32 of the distributor mechanism (Fig. 4). While said post end 32 is made of insulating material, it is screwed in a metallic post 33, which in

turn is secured to a metallic plate 34 suitably insulated from crank shaft 35 by insulation 36, a return wire 37, held between said post end 32 and said post 33, leading to the spark plug 38 of one of the motor cylinders. The screw 39 passing through post end 32 conducts the current from wire 31 to the flat spring 40, which is in constant contact with the distributing cylinder 41 mounted on crank shaft 35 and suitably insulated therefrom as by insulation 42, whereby current is constantly passed through said distributing cylinder.

As many binding posts 46 as may be necessary are attached to plate 34, each post 46 carrying a wire 43 for conducting current to one of the spark plugs of the motor, each of said posts 46 carrying also a flat spring 44 which is always in contact with the lower portion of the distributing cylinder 41, the major part of which is made of insulating material as 45. A projecting metallic part 47, on said distributing cylinder 41 at a point horizontally opposed to flat springs 44 serves to distribute current to the proper one of wires 43 or wire 37 whenever said projection 47 comes in contact with any of springs 44 on the rotation of crank shaft 45, the mechanism being properly synchronized to operate effectively.

In the operation, as will be apparent, the motor 10 and propeller 11 will rotate in one direction, and the propeller 15 in an opposite direction. By making the propeller 11 of considerably greater size than the propeller 15 the increased resistance to the air will cause the propeller 11 to rotate relatively slowly while at the same time it will be assisted in its rotation by the air current from the front propeller 15. As shaft 16 rotates about shaft 17 it receives fuel therefrom, which fuel is conducted through pipes 23 to the cylinders.

Spring 30 rotates on disk 34 receiving current therefrom and conducting the cur-

rent to screw 39, therethrough to spring 40 and distributing cylinder 41, to projection 47 and from said projection to spring 44 and wires 43 to the spark plugs 38. Plate 34 rotates with the motor, while distributor cylinder 41 rotates with the crank shaft, whereby the relative rotation is increased on the rotation of the motor 10 with propeller 11, and the proper timing is retained.

What I claim is:

1. In an aeroplane power plant, a propeller, a motor for driving said propeller arranged for rotation in a direction opposite to that of said propeller, and means for supplying electric current to said motor, including a stationary disk connected to a source of electrical current, a spring rotatable with the motor and in contact with said disk, a rotatable distributing cylinder fixed upon and insulated from the motor shaft, means electrically connecting said spring and said cylinder, and means for conducting current from said cylinder to the spark plugs of said motor.

2. In an aeroplane power plant, a propeller, a motor for driving said propeller and arranged for rotation in a direction opposite to that of said propeller, and means for supplying electric current to said motor, including a stationary disk connected to a source of electrical current, a plate fixed to and insulated from the crank case of the motor, a distributing cylinder fixed upon and insulated from the shaft of the motor, said distributing cylinder having one end thereof presenting a metallic surface completely therearound and a second portion presenting an insulating surface having a metallic projection at one point, and binding posts upon the said plate having members engaging the said cylinder.

In testimony whereof I have affixed my signature this 5th day of June, 1920.

PAUL PETRES.
